UNITED STATES PATENT OFFICE.

HARRY M. DUNGAN, OF JEFFERSON CITY, MISSOURI.

ADJUSTABLE SHELF.

1,080,203.

Specification of Letters Patent.

Patented Dec. 2, 1913.

Application filed November 6, 1912. Serial No. 729,778.

To all whom it may concern:

Be it known that I, HARRY M. DUNGAN, a citizen of the United States, residing at the city of Jefferson City and State of Missouri, have invented a new and useful Adjustable Shelf, of which the following is a specification.

This invention relates to shelves and more particularly to shelves of adjustable type and consists in the novel design and arrangement of parts hereinafter more fully disclosed.

An object of the invention is to provide shelves of durable and inexpensive construction which are readily and conveniently adjustable so as to space the shelf members at any definite predetermined intervals to receive or accommodate books or like articles placed thereon.

20 Another object is to provide suitable sustaining members upon which the shelves may be removably mounted, said means for mounting the shelves being so arranged that when the shelves have been adjusted and the 25 books or other like objects placed thereon, the shelves will be locked in position and thus prevented from displacement until the objects carried thereby shall have been removed.

30 With these and other obvious objects in view, I have designed, combined and arranged the several parts or elements in the manner hereinafter described and claimed, reference being made to the accompanying 35 drawings in which like characters of reference indicate like parts throughout the several views, in which—

Figure 1 is a perspective view of a section of the shelving embodying the present invention, clearly illustrating the several parts in assembled relation. Fig. 2 is a plan view showing one of the partition elements in horizontal section, designed particularly to illustrate the manner in which the partition 45 elements and the shelves with their supporting members are assembled. Fig. 3 is a side elevation of a portion of one partition element showing one of the shelves in cross-section mounted in assembled adjustment. 50 Fig. 4 is a vertical section taken through one of the partition elements adjacent to the rear end thereof, showing also a fragment of one

of the shelves in longitudinal section held in place by a sustaining element or bolt, and Fig. 5 is a detail view of a preferred form 55 of sustaining bolt upon which the shelves rest.

In the embodiment of my invention illustrated in the drawings, A indicates the partitions or uprights which comprise preferably a double partition wall 1 which is preferably of flexible metal bent as clearly illustrated in Fig. 1 to form a double wall which is U shaped in cross-section and which has outwardly extending flanges 2 at its rear or 60 inner edge. Vertical posts or plates 3 of somewhat heavier and more substantial construction and to which the partition elements are bolted by bolts 4, serve to give the stack rigidity and strength. The plates 3 65 are preferably provided with projections or rectangular beads 5 which extend for a slight distance into the hollow portion between the walls 2 thus providing additional strength and stiffness to the construction of 70 the stack, as will be readily understood. The partition walls A are supported apart by plates 6 bolted preferably to the inner face of the flanges 2, the bolts passing through the plates 3, said plates 6 constituting, as 75 will be understood, stiffening and strengthening members for holding the partitions A in vertical position parallel one with the other. Through each of the walls, of each 80 of the partition elements A, are cut two series of vertical slots 7 arranged adjacent to the outer and inner edges of said partitions, respectively, in the manner clearly illustrated in Fig. 1. The slots of each series 85 are staggered, with respect to each other, and are arranged so that the slots in each vertical line will overlap those in the other, in order that the sustaining members or bolts may be seated at any desired vertical position 90 in the partition elements. The purpose 95 of staggering the slots in this manner is to prevent a weakening of the partition walls which would result from a continuous vertical slit through the metal. Formed thus in staggered relationship the strength of the 100 walls of the partition element remains practically the same as if the sheet forming the wall contained no slots at all and yet the sustaining bolts, as has been explained, may

be positioned at any desired vertical adjustment. It will be, of course, understood that the partition element, such for instance as the partition element shown to the left of Fig. 1 which forms the outer side of the stack, contains no slots in its outer face, the intermediate partitions, however, have both walls slotted so as to provide seats for sustaining bolts for supporting shelves on both sides of the partition, as will be readily understood.

Each of the shelves 8 is constructed preferably of a sheet of flexible metal which is rounded to form a bead 9 at its inner and outer edge so as to prevent defacement of books or other like objects as they are moved into place upon the shelves. At each end of the shelves 8 is provided a depending web or flange 10, formed preferably as shown in Fig. 3 with a triangular depression or cut-out portion so that when books are tilted forward, in removing them from the subadjacent shelf, the upper edges will pass into the cut-out portion thus permitting the shelves to be adjusted closer together, as the upper inner corner of the book, as it is withdrawn from the shelf, may extend upwardly to the under face of the shelf above without being interfered with by the flange or web 10. Each of the flanges formed at the ends of the shelf member 8 is provided, adjacent to its outer end, with vertical slots 11 which are spaced to register with the forward staggered slots 7 in the partition elements A. Each of said flanges or webs 10 is also provided with a second series of slots 12 which extend obliquely inwardly so that when the sustaining element or bolt 13 is seated in one of the slots 11 and the shelf element 8 tilted backwardly to bring it to adjustment, the rear sustaining element will be conveniently and readily seated in the corresponding slot 12. It will be observed that as the shelf is brought to horizontal position and the rear bolts seated in the slots 12, as described, it will be impossible to raise the shelf element vertically upwardly, as the rear sustaining bolt would bear against the side of its corresponding slot 12 thereby preventing accidental displacement of the shelf by vertical pressure on the shelves 8.

The sustaining bolts 13 are constructed substantially as shown in Fig. 5, with a flat head 14 which, in assembling the shelves, is inserted into the proper slot in the partition A and turned at right-angles so that the said head will bind against the inner edge of said slot and, as will be understood, said bolts are adapted to coöperate with threaded sleeves 15 to bind the shelves in proper adjustment. Each of the threaded sleeves 15 may be provided with a knurled flange 16 so that the sleeve may be readily

manipulated; and may be also provided with a hexagonal head 17 to permit adjustment with a wrench if desired.

Having thus fully described my invention, so as to enable those skilled in the art to which this invention appertains to make and use the same, what I claim and desire to secure by Letters Patent is:

1. Shelf construction comprising, in combination, partition elements provided with two series of staggered slots arranged adjacent to the front and rear edges of the partition elements and the slots in each series overlapping at their ends, shelf sustaining bolts arranged to be seated in said slots, shelves provided with depending flanges at each end thereof, said flanges being provided at their front ends with two vertical parallel slots and at their rear ends with two parallel inclined slots, said slots adapted to engage over the sustaining bolts carried by the slots in said partition walls, and means for binding said bolts and shelves in any desired vertical position, substantially as specified. 90

2. Shelf construction comprising partition elements formed from a sheet of flat metal bent to form a double wall substantially U-shaped in cross-section and being provided with outwardly extending flanges at their inner ends and reinforcing plates bolted to said flanges; said walls having formed therein a series of vertical slots adjacent to the front and rear edges thereof, respectively, and the slots of each series overlapping at their adjacent ends, lateral reinforcing elements bolted to said flanges and adapted to sustain said partition elements in vertical parallel adjustment, sustaining bolts adapted to be inserted and locked in said slots, shelf elements comprising a sheet of flat metal rounded at the edges and being provided with depending flanges at their extremities, said flanges being provided with parallel slots arranged adjacent to the front and rear edges thereof, the slots adjacent to the front edge being arranged parallel and vertical with respect to the said flat sheet, and the slots adjacent to the rear edge being inclined backwardly and downwardly, with respect to said sheet, and a binding sleeve, manually operable, adapted to co-operate with said bolts for binding said shelf element and said partition elements together, substantially as specified. 110

3. Shelf construction comprising, end walls of double plates, and having vertical staggered and overlapping slots in both plates adjacent the front and rear edges thereof, shelf elements provided with flanges supported at right angles and having vertical parallel slots in said flanges adjacent one edge of said shelf elements, and parallel inclined slots in said flanges adjacent the 125 130

other edge of said shelf elements, shelf supporting bolts seated in the slots in said end walls and extending inwardly permitting the slots in the shelf elements to be engaged thereover, and means for binding bolts and shelf elements in any desired vertical adjustment, substantially as specified.

In witness whereof, I have signed this specification in the presence of two subscribing witnesses.

HARRY M. DUNGAN.
